MOTOR HEAD HANDLE

Dugan L. Bowen, Hydro, Okla.

Application June 12, 1939, Serial No. 278,782

1 Claim. (Cl. 294—15)

This invention relates to a head handle for motors and has for an object to provide a simple tool which may be easily applied to the heads of overhead valve and valve in head motors or to the heads of L head motors for lifting the head from the motor to permit inspection and repair of the valves.

A further object is to provide a device of this character which will be formed of a few strong simple and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a perspective view of the device.

Figure 2 is a cross sectional view of the device in applied position on an overhead valve and valve in head motor.

Figure 3 is a cross sectional view of the device applied to an L head motor.

Referring now to the drawing in which like characters of reference designate similar parts in the various views, 10 designates a single length of strap metal deformed to provide a substantially U-shaped handle, the arms 11 of the handle being each twisted axially upon itself as shown at 12 adjacent the longitudinal base of the handle. The upper ends of the arms 11 are directed outwardly as shown at 13, and then directed upwardly to provide lugs 14.

A grip formed of a metal rod 15 is provided near the ends with loops 16 formed of strap metal, the ends 17 of each loop being disposed parallel with each other and abutting a respective one of the lugs 14. Bolts 18 are passed through apertures 19 in the lugs 14 and through apertures 20 in the ends 17 of the loops 16 to secure the grip 15 to the handle 10. Stop caps 21 are threaded secured on the ends of the grip.

The longitudinal base of the handle 10 is provided with apertures 22 to receive the conventional rocker arm bolts 23 of the head of an overhead valve and valve in head motor 24. Adapters 25 are provided to mount the device on an L head motor 26. The adapters 25 are adapted to be threaded into the spark-plug openings of the L head motor and are provided with bolts 27 which are directed through the apertures 22 in the handle. The bolts receive nuts 28 to secure the handle 10 to the head.

Recesses 29 are provided on the inner side of the longitudinal base of the handle 10 to clear stud-head bolts on a motor head.

In operation, the U-shaped handle is easily applied to an overhead valve and a valve in head motor 24 by inserting the rocker arm bolts 23 of the head through the apertures 22 in the handle 10 to draw the longitudinal base of the handle tight against the head. Adapters 25 are threaded into the spark-plug holes of an L head motor 26 and then the bolts 27 are engaged through the apertures 22 of the base of the handle. The nuts 28 are then applied to the bolts to hold the handle 10 tight against the head. In either case by lifting up on the grip 15 the head can easily be lifted from the motor or lifted back in place as the case may be.

In case the head should become stuck at one end as is often the case the bolts 18 are loosened and the grip 15 is slid endwise through the loops 16, until one of the stop caps 21 checks the movement of the grip in that direction. The bolts 18 are then tightened to hold the grip from slipping through the loops. The grip may then be used as a lever to pry up the head of the motor, and break it loose without damaging the head. The usual practice of tapping the head when stuck with a hammer, or using a screwdriver in a spark plug hole, or both, causes heads to become broken.

From the above description it is thought that the construction and operation of the invention will be fully understood without further explanation.

What is claimed is:

A head handle for motors comprising a single length of strap metal deformed to provide a substantially U-shaped handle, the upper ends of the arms being directed outwardly then upwardly to provide lugs, an adjustable grip formed of a metal rod, loops formed of strap metal disposed on the grip near its ends, the ends of each loop being disposed parallel and abutting a respective lug, bolts passed through said ends of the loops and said lugs to secure the adjustable grip to the handle, and stop caps secured on the ends of the grip, the longitudinal base of the handle being provided with apertures arranged in a longitudinal row on the said base to receive rocker arm bolts in the head of an overhead valve or valve in head motor for drawing the handle tight upon the head, said grip being of greater length than said base to provide a lever capable of adjustment endwise through said loops until one of said stop caps engages the respective loop, to permit prying loose of a stuck motor head.

DUGAN L. BOWEN.
